UNITED STATES PATENT OFFICE.

JOHN LEWISOHN, OF NEW YORK, N. Y.

METHOD OF MAKING COLORED PHOTOGRAPHIC REPRODUCTIONS.

1,071,559.

Specification of Letters Patent. Patented Aug. 26, 1913.

No Drawing.

Application filed January 12, 1911. Serial No. 602,196.

To all whom it may concern:

Be it known that I, JOHN LEWISOHN, a citizen of the United States, and a resident of the city of New York, borough of Manhattan, in the county and State of New York, have invented a new and Improved Method of Making Colored Photographic Reproductions, of which the following is a full, clear, and exact description.

10 My invention relates generically to a method of making reproductions and specifically relates to the utilization of the blue coloration in a blue-print as one of the primary colors to combine with suitable red and 15 yellow color washes or diluents to modify the blue effect to form the desired color effects, and, at the same time, to retain the fine shade values and soft relatively true tones of the original blue-print.

20 My invention pertains to a process or method in which I make use of the original blue color of a blue-print reproduction as one of the primary spectrum colors, and make use of red eosin for the red and aurantia for the yellow. By the mixture of these 25 three colors, I am able to obtain substantially any of the spectrum colors.

A negative of a colored object is made 30 preferably on an ordinary orthochromatic photographic plate, having as a basis the silver emulsion, and preferably using a yellow colored screen, in order to obtain the best color values. From such a negative, an ordinary blue-print is made, which blue-print will, of course, show up the different 35 shade values in their proper proportions. This blue-print is then colored either wholly or in part, by applying dye or paint, but preferably red eosin and aurantia, or a mixture of the two, to modify the blue to form 40 any of the spectrum colors, the blue coloration showing through the applied washes with more or less intensity depending upon the extent of the coating wash. Should it 45 be desired to make all or any material portion of the print either red or yellow, or any other color, in which blue is not used, the blue of the blue-print is either wholly or 50 partially dissolved by a weak solution of nitrate of silver, which will fix the colors, and, at the same time, will gradually bleach out the blue. Further, the blue-print may

be washed with this solution, if it is desired to merely weaken the blue color of the object, after the eosin or aurantia has been applied, or a mixture of the two, to form any of the spectrum colors involved in these two primary colors. Should it be desired to restore the blue locally or entirely, or to darken the blue color, the blue-print is respectively touched up or bathed with a solution of ferric chlorid, and this ferric chlorid may be applied in stronger solution or in succession until that part of the object is practically black. Instead of painting or bathing the entire print in any one of these colors, certain spaces may be touched up locally, in order to either darken or lighten those particular parts. In addition to this local treatment, the entire print may be submerged in either of these primary colors, or any combination of the same, to give the different color background and a different tint to the entire picture.

Having thus described my invention, I claim as new and desire to secure by Letters Patent:

1. The process of reproducing on blue-prints from yellow screened negatives, the color effects resembling the natural colors and tones of objects while retaining the shade values inherent in such prints, which process consists in locally treating the shaded portions which should be red-blue with a thin red wash, the shaded portions which should be blue-yellow with a thin yellow wash, and the shaded portions which should be deficient in blue with a blue dissolving substance.

2. The process of reproducing on blue-prints from yellow screened negatives, the color effects resembling the natural colors and tones of objects while retaining the different soft, relatively true shade values inherent to such prints, which process consists in locally treating the shaded portions which should be red-blue with a thin red wash, the shaded portions which should be blue-yellow with a thin yellow wash and the shaded portions which should be deficient in blue with a blue dissolving substance, and then with a yellow, red, or red and yellow wash.

3. The process of producing on blue prints

a plurality of color effects which consists in treating a blue print which displays a plurality of shades or tones, or any portion of a blue print displaying a plurality of 5 shades or tones, with a thin uniform wash of a pigment of a hue other than blue.

In testimony whereof I have signed my

name to this specification in the presence of two subscribing witnesses.

JOHN LEWISOHN.

Witnesses:

W. S. ORTON,
PHILIP D. ROLLHAUS.
